COMBINED CAN OPENER AND KNIFE SHARPENER

Melvin H. Boldt, Glenview, Ill., assignor to National Presto Industries, Inc., Eau Claire, Wis.

Filed Feb. 1, 1973, Ser. No. 328,521

Term of patent 14 years

Int. Cl. D7—99

U.S. Cl. D8—35

FIG. 1 is a front elevational view of a combined can opener and knife sharpener showing my new design; the front wall thereof being recessed within a surrounding marginal rim as illustrated by the fragmented section of FIG. 4;

FIG. 2 is a rear elevational view thereof;

FIG. 3 is an elevational view of one side thereof;

FIG. 4 is an elevational view of the opposite side, a portion thereof being sectioned;

FIG. 5 is a top plan view thereof; and

FIG. 6 is a bottom plan view thereof.

I claim:

The ornamental design for a combined can opener and knife sharpener, substantially as shown and described.
